Fig 1

Fig 2

Fig 3

Fig 4

Fig 5

FIGURE 1 is a front perspective view of a self-feeder for small animals, on a somewhat reduced scale, showing my new design.

FIGURE 2 is a front view thereof;

FIGURE 3 is a side elevation thereof;

FIGURE 4 is a rear elevation thereof; and

FIGURE 5 is a top plan view thereof.

The undisclosed side of the feeder is substantially like the side shown.

I claim:

The ornamental design for a self-feeder for small animals, substantially as shown and described.
